[57] ABSTRACT

A tracer device is provided for a rocket and comprises at least one sheath arranged at the rear of the rocket and containing a pyrotechnical charge whose combustion produces a flame enabling the rocket to be followed along its trajectory. The sheath terminates in a convergent-divergent nozzle and the axis of the sheath is inclined with respect to the longitudinal axis of the rocket so as to direct the flame into the region comprised between the inside boundary of the air stream flowing behind the rocket and the outer boundary of the propellant gas jet.

FIG. I

FIG. 2

FIG. 3

TRACER DEVICE FOR A ROCKET

BRIEF SUMMARY OF THE INTENTION

The present invention relates to a tracer device for rockets and similar vehicles to enable tracking of such vehicles in their flight path. The tracer device emits a flame arising from the combustion of a pyrotechnical charge.

It has long been established that such tracers exhibit appreciable losses in flight in comparison to the results obtained when measurements were made from a reference point. This loss of power is due to distance, but also to eddies caused by the airstream lines along the body of the vehicle at the moment when they leave the body at the rear thereof, the tracer device being located on the body. These eddies are particularly violent above supersonic speeds. Moreover, wind velocity and direction also produce disturbing effects on the tracer flame when the velocity is subsonic.

Attempts have been made to remedy these drawbacks. Thus, it is known to arrange deflectors on tracers, at the outlets thereof, so as to maintain the apparent diameter of the flame appreciably constant or to lengthen the vehicle with a cowling surrounding the flame so as to create a less turbulent zone therearound.

An object of the present invention is to remedy the aforesaid drawbacks in a novel way.

According to the invention, the tracer device for a rocket or similar vehicle comprises at least one sheath arranged at the rear of the rocket and containing a pyrotechnical charge whose combustion produces a flame allowing the rocket to be followed along its trajectory and the tracer device is characterized in that the sheath terminates in a nozzle of convergent-divergent form, the centerline of the sheath being at an angle to the longitudinal axis of the rocket so as to direct the flame into the region between the inner boundary of the air streams emerging behind the rocket and the outer boundary of the propellant gas jet.

According to a preferred construction, the sheath is fitted at an inclination on one of the ends of a rotatable cylindrical block which is embedded at its other end in a housing extending parallel to the longitudinal axis of the rocket.

Preferably the angle between the axis of the sheath and the axis of the cylindrical block lies between 25° and 60°.

The nozzle of the sheath allows the incandescent particles issuing from the combustion of the pyrotechnical charge to be given sufficient velocity for them to cross the turbulent zone and reach the region where the flows of propellant gas and air run side-by-side, whereby there is produced an extension of the flame. Proper guidance of the flame is obtained through the adjustment of the inclination of the sheath on the cylindrical block in conjunction with the adjustment of the latter in the housing.

BRIEF DESCRIPTION OF THE DRAWING

FIG. 1 diagrammatically illustrates the aerodynamic phenomena occurring at the rear of a rocket equipped with a tracer device according to the invention and moved under the effect of a propellant;

FIG. 2 shows partly broken away and in section two components of the tracer device;

FIG. 3 is a perspective view of one component of the device; and

FIG. 4 is an axial section of a sheath containing the pyrotechnic charge inside the element of the device.

DETAILED DESCRIPTION

Referring to FIG. 1 of the drawing therein is seen the rear portion of a rocket F as shown in motion in the air. The rear portion of the rocket F is provided with stabilizing fins a. A propellant gas jet b issues from a nozzle c at the rear of the rocket and the gas jet b expands progressively and approaches the air stream layer d which travels along the body of rocket F. A space e is formed between the inner boundary f of the air stream layer d and the outer boundary g of jet b. In this space are produced vortices h particularly at the rear face of rocket F.

According to the invention, rocket F carries at its rear a tracer device for emitting a flame 2, and this device comprises two elements 1 which are embedded by means of a synthetic resin 3 in housings 4 arranged diametrically around nozzle c of rocket F.

Each element 1 is composed of a sheath 5 mounted perpendicularly at its base 6 at the center of a sloping surface 7 of a cylindrical block 8 which is secured in housing 4. By this arrangement, the axis of sheath 5 is offset by an angle i from the axis of the cylindrical block 8. The magnitude of angle i is between 25° and 60°.

At its free end, sheath 5 terminates in a nozzle comprising a convergent portion 9 and a divergent portion 10.

Sheath 5 is a one-piece body and is lined internally with a polyester resin layer 11 containing a refractory metal oxide. The sheath 5 contains in its cylindrical portion a pyrotechnical charge 12, the combustion of which gives rise to flame 2 emerging at the outlet of the divergent portion 10.

In one preferred embodiment, the casing of sheath 5 is constituted of metal, graphite or a thermosetting 40 molded plastic. The molded plastic material is advantageously fabricated from a base of phenolic molding powder containing asbestos.

The internal lining of polyester resin 11 in sheath 5 containing the refractory charge insures the thermal safety of the jacket of the sheath. In a preferred form, the refractory metal oxide is magnesium oxide. Other metallic oxides resistant to heat are suitable such as zirconium oxide and the like.

The tracer device produces flame 2 directed at an 50 inclination with respect to the longitudinal axis of rocket F toward the region where the air stream layer d and the gas jet b come together. This is achieved through adjusting the angle i of sheath 5 on block 8, the value of i resulting from a preadjustment of the position of block 8 around its axis before it is secured in the housing 4. In this respect block 8 may be rotatably mounted in the housing and after suitable adjustment it becomes embedded in resin 3. It is recalled that surface 7 of block 8 is a sloping surface, and therefore the angle i between the axis of the sheath 5 and the axis of the block 8 depends on the position of the block 8 around its axis.

The discharge velocity of the incandescent particles in flame 2 is remarkably increased by the nozzle end of sheath 5, so that flame 2 easily crosses the turbulence zone h and is, in a fashion, seized by the air and gas flows, the result of which is to lengthen flame 2.

It follows from this that the apparent diameter of the flame 2 as seen by an observer is appreciably increased and consequently the potency of the tracer device according to the invention is remarkably enhanced.

WHAT IS CLAIMED IS:

1. For a rocket having a rear portion with a propellant jet emitted therefrom along the longitudinal axis of the rocket and which expands rearwardly to approach an air stream layer around the rocket, a tracer device comprising means for producing a tracer flame at the rear portion of the rocket between the outer boundary of the propellant jet and the inner boundary of the air stream layer, said means comprising a sheath supported in said rear portion of the rocket and having an outlet nozzle, the axis of said nozzle being outwardly inclined at a rearwardly diverging angle with respect to the longitudinal axis of the rocket, and means in said sheath for generating said tracer flame.

2. A tracer device as claimed in claim 1 wherein said outlet nozzle is a convergent-divergent nozzle.

3. A tracer device as claimed in claim 2 wherein the rear portion of the rocket is provided with an opening constituting a housing and said means further comprises a cylindrical block mounted in said housing and

supporting said sheath.

4. A tracer device as claimed in claim 3 wherein said cylindrical block has an axis extending parallel to said axis of the rocket and an outer face inclined with respect to said axis of the block.

5. A tracer device as claimed in claim 3 wherein said sheath has an axis which is inclined with respect to the axis of the block by an amount between 25° and 60°.

6. A tracer device as claimed in claim 3 wherein said means further comprises a synthetic resin in said housing embedding said cylindrical block therein.

7. A tracer device as claimed in claim 1 wherein said sheath is constituted of one element of the group consisting of metal, graphite and thermosetting plastic material.

8. A tracer device as claimed in claim 7 comprising asbestos in said thermosetting plastic material.

9. A tracer device as claimed in claim 1 wherein said sheath includes an internal lining of a powdered refractory metallic oxide.

10. A tracer device as claimed in claim 9 wherein said metallic oxide is magnesium oxide.
